UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

WIRE FASTENER.

Application filed October 6, 1924. Serial No. 741,942.

My invention relates to improvements in wire fasteners particularly adapted for attaching wire lath in outstanding relation to the wall sheathing of stucco structures; 5 and one of the objects thereof is the provision of an inexpensively constructed spacing-clip slidably carried on the forward end of a nail; a further object is the provision of a spacing-clip constructed of sheet metal, 10 that may be "blanked" and "formed" by one stroke of the press.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what 20 is claimed without departing from the spirit of the invention.

In the accompanying drawings—

Figure 1 is a side elevation of a wire fastener constructed in accordance with my invention, disposed in position for driving into the wall sheathing of a stucco structure, and a cross section of a portion of wire lath;

Figure 2 is a side elevation of the wire fastener in its final position after being driven into the wall sheathing as far as it is intended to operatively go, a portion of the wire lath confined between the nail head and the spacing-clip, and a section of stucco composition in the immediate background;

Figure 3 is a front elevation of the fastener;

Figure 4 is a sectional plan view on line 40 4'-4', Fig. 1;

Figure 5 is a cross section on line 5'-5', Fig. 1;

Figure 6 is a vertical sectional view on line 6'-6", Fig. 4, but with the nail and lath 45 omitted;

Figure 7 is a view on line 7'-7', Fig. 1;

Figure 8 is a view on line 8'-8", Fig. 1;

Figures 9 and 10 are side and front views respectively of a modified form of the invention;

Figure 11 is a cross section on line 11'-11", Fig. 9;

Figure 12 is a cross section on line 12'-12", Fig. 9;

Figure 13 shows a blank stamping, ap-

proximately, of the spacing-clip of the preferred form of the device; and

Figure 14 shows the approximate blank of which the spacing-clip of the modified form is constructed.

Referring to the drawings in detail, throughout which like reference characters designate like parts:

The numerals 1, 2, 3 and 4, designate, respectively, the wall sheathing, the wire lath, 65 my improved wire fastener, and the stucco composition, which form the exterior portions of the walls of stucco structures.

The wall sheathing 1 comprises the usual boards secured across the face of the frame timbers of the wall, or, it may comprise any other suitable wall covering secured to the wall timbers.

The wire lath 2 may comprise any suitable mesh wire fabric, including the fabric 75 commonly known as "poultry netting".

The wire fastener 3 comprises, a nail having the usual cylindrical shank 5 and flat head 6, and a spacing-clip 7, the latter which is formed of a strip of sheet metal, comprises (referring now more particularly to the preferred form of the invention) a body portion 8, which terminates at its lower end in an outwardly extending supporting-base 9 and at its upper end in an outwardly extending lath seat 10, the free end of which being curved upwardly to form a lath-retaining lip 11.

An intermediate portion of the body portion 8 is struck rearwardly to form an arcuated securing band 12, while portions of said body portion above and below said securing band, are struck forwardly to form an upper arcuated indentation 13 intersecting with the lath seat 10, and a lower arcuated indentation 14 intersecting with the supporting-base 9.

The arrangement of said securing band 12 and indentations being such as to provide a vertical opening therebetween, of which the securing band 12 forms the rear wall and the indentations 13 and 14 the front wall, and through which opening projects the shank 5.

The spacing-clip 7 is intended to be "factory-built" onto the forward end of the nail, and is intended to engage and embrace the shank 5 with sufficient clasping tension to become normally frictionally locked thereon against movement relative thereto, but

vertically slidable thereon against the resistance set up by said clasping tension, when the nail is driven into the wall sheathing against which the spacing-clip may be seated.

The modified form, as shown in Figs. 9, 10, 11 and 12, differs from the preferred form mainly in the method employed for securing the spacing-clip to the nail shank. 10 In this form the body portion 8 is provided with a central indentation 15 intersecting with and extending from the supporting-base 9 upwardly into intersection with the lath seat 10, and with a pair of side wings 15 16, which comprise opposed lateral extensions on the margins of said body portion bent backwardly into engagement with the shank 5 for holding it in the indentation 15.

The spacing-clips 7 are adapted as furring means for holding the lath 2 a distance away from the face of the wall sheathing 1, while the nails are adapted to bind the lath against the clips and to secure them and the lath to the face of the wall sheathing.

25 The lath 2 is intended to form outstanding reinforcement and support for the stucco composition 4, the latter adapted to be applied by spreading it on the wall sheathing and on and around the lath 2 and the protruding portions of the spacing-clips 3.

To apply my improved wire fastener for attaching the lath after it has been disposed across the face of the wall sheathing, the fasteners are applied one at a time and projected at suitable spaced apart intervals, through the meshes of the lath, with the lath seats 10 disposed directly underneath the lath wires to be secured (see Fig. 1), after which the nails are driven forward 35 until the heads 6 engage and bind the lath wires firmly against the lath seats (see Fig. 2).

I claim:

1. In a wire fastener of the character described, a nail having a head, a spacing clip formed of a strip of sheet metal comprising a body portion disposed in a vertical plane and having a loop struck therefrom and through which said nail is frictionally held, the entire lower end of said body portion bent over to one side to form a supporting base and the upper end of said body portion bent over to one side to form a lath seat.

2. In a wire fastener of the character described, a nail having a head, a spacing clip formed of a strip of sheet metal comprising a body portion disposed in a vertical plane and having a loop struck therefrom and through which said nail is frictionally held, 55 the lower end of said body portion bent over to one side to form a supporting base and the upper end of said body portion bent over to one side to form a lath seat, said lath seat having an upwardly projecting lath retaining lip.

3. In a wire fastener of the character described, a nail having a head, a spacing clip formed of a strip of sheet metal comprising a body portion disposed in a vertical plane and having opposed loops struck 70 therefrom between which said nail is frictionally held substantially in the plane of said body portion, the entire lower end of said body portion bent over to one side to form a supporting base and the upper end 75 of said body portion bent over to one side to form a lath seat.

4. In a wire fastener of the character described, a nail having a head, a spacing clip formed of a strip of sheet metal comprising 80 a body portion disposed in a vertical plane and having opposed loops struck therefrom between which said nail is frictionally held substantially in the plane of said body portion, the lower end of said body portion bent over to one side to form a supporting 85 base and the upper end of said body portion bent over to one side to form a lath seat, said lath seat having an upwardly projecting lath retaining lip.

5. In a wire fastener of the character described, a nail having a head, a spacing clip formed of a strip of sheet metal comprising a body portion disposed in a vertical plane and having a loop struck therefrom and 90 through which said nail is frictionally held, the entire lower end of said body portion bent over to one side to form a supporting base and the upper end of said body portion bent over to the same side to form a lath 95 seat.

In testimony of the foregoing being my own, I have hereunto affixed my signature this 30th day of September, 1924.

GEORGE F. VOIGHT.
